PIPE SUPPORT MODULE

Alex W. Bolt, 1408 Richmond 255,
Houston, Tex. 77006

Filed Apr. 19, 1974, Ser. No. 462,399

Term of patent 14 years

Int. Cl. D8—08

U.S. Cl. D8—235

fig. 1

fig. 2

fig. 3

FIG. 1 is a perspective front view of a pipe support module showing my new design;

FIG. 2 is a front elevation thereof; and

FIG. 3 is a top view thereof.

I claim:

The ornamental design for a pipe support module, as shown.
